UNITED STATES PATENT OFFICE.

HENRY V. C. HOLLAND AND WILLIAM H. WIGGINS, OF BROOKLYN, NEW YORK.

BOWLING-ALLEY.

1,068,131.

Specification of Letters Patent. Patented July 22, 1913.

Application filed September 16, 1912. Serial No. 720,617.

To all whom it may concern:

Be it known that we, HENRY V. C. HOLLAND and WILLIAM H. WIGGINS, citizens of the United States of America, and residing at Brooklyn, in the county of Kings and State of New York, have invented new and useful Improvements in Bowling-Alleys, of which the following is a specification, like characters in the drawings designating like parts.

This invention relates to bowling-alleys, and has for its primary object the provision of means for the return of the bowling balls from the pit end of the alley to the approach end by means of an overhead return-ball runway or track, in order that the space required for the return of the aforesaid balls need not be taken from that available for the construction of the alleys proper, and thus more alleys can be built within a given area than heretofore.

Another important object of our invention is to construct the return in such manner as to afford an unobstructed view of all alleys operating and to leave the foul line entirely clear and free from racks and newel posts, inasmuch as return ball-runways, as constructed heretofore, have interfered materially with the freedom of the player, distracting his attention, and diminishing the accuracy of his play.

Among other important objects of our invention, is the provision of means to elevate the ball at the pit end of the overhead track, with means preferably to enable this elevator to be operated automatically or by hand, use being made preferably of a weight tending normally to maintain the elevator at its highest position adjacent to the point at which the ball is discharged from the elevator into the overhead track on its path to the approach end of the alley. We prefer to provide also means by which the elevator can be depressed to receive the ball for elevation and in connection therewith means to retain the elevator in its depressed position until released by the entrance of the ball into the elevator, other means being preferably provided by which when the ball has been discharged from the elevator at its high point, the latter is drawn by a suitable power device down into its depressed position and there caught ready to receive and

elevate another ball. For this purpose we prefer to provide an electric motor controlled by electric contact-devices, to be described more in detail hereinafter.

Other important objects of our invention comprise the provision of an elevator of ball-retaining construction, to prevent accidental displacement of the ball during its elevation, and in combination therewith an ejector, acting automatically to discharge the ball from the elevator when the latter reaches its high point opposite the entrance to the track; also the provision of two runways, or tracks, at the point of discharge from adjacent elevators, merging into a single track at a suitable distance from the point of discharge, so that one track serves in general for the return of balls from a pair of alleys, and in connection with this double-service we prefer to provide the entrance track portions at slightly different heights, so that if balls arrive at the junction at approximately the same time, the point of contact will be off the dead center overcoming any tendency of the balls to jam in the opening of the main single run-way, and we prefer to provide guide rails at approximately the center line of the balls on each side to prevent escape from runway. We have provided also a run-way or track structure of anti-vibrating character, thus to avoid unnecessary noise and interference with the attention of the players.

Other important objects comprise means to check the motion of the ball upon its arrival at the approach end and supply rack, so that substantially all momentum is exhausted, and this we prefer to accomplish by a tortuous upright portion at the point at which the overhead track drops into the supply rack. Moreover this construction makes it possible to set the supply rack well back of the foul line either parallel with or at any desired angle to the alley; leaving the foul line clear and entirely unobstructed.

The various features of our invention will be illustrated and described fully in the accompanying drawings and specification and pointed out in the claims.

In the drawings: Figure 1 is a view in cross section, of a somewhat diagrammatic character, showing portions of several adjacent bowling alleys, with an elevator in

the construction of which our improvements have been embodied; Fig. 2 is a fragmentary view of the upper portion of the elevator and of the adjacent entrance portions of a plurality of tracks; and Fig. 3 is a view in vertical section, partly in end elevation, of said double track portion, looking from left to right, Fig. 2, while Fig. 4 is a view of a somewhat diagrammatic character, showing 10 the approach portion of our improved overhead return runway for bowling alleys, in side elevation.

In the embodiment of our invention selected for illustration and description to 15 permit ready and complete understanding of our improvements, the part designated by the reference numeral 1 is a bowling alley which may be of any suitable construction, and is shown as of well-known form, 20 comprising the alley proper, or alleys, respectively bearing the numerals 3 and of which there may be any convenient number, and beside which may and preferably will be provided suitable gutters 5 and divisions 25 7 which at the pit ends rise to form "kick backs" 9 on which are mounted convenient seats 10 for the use of the "pin boys."

In accordance with our invention, a return track 11 is provided above the level of 30 the players' heads, running from the pit to the approach end, the entrance portion of this track being shown in Figs. 2 and 3, while the delivery portion is shown in Fig. 4, on a somewhat smaller scale, the middle 35 portion being broken away, inasmuch as its extent is immaterial. This overhead track may be of any material and form suitable to convey the balls 2 and for the sake of lightness and quiet operation, it may be 40 composed of pipes or wooden strips 13, carried by a suitable support, such as the ceiling 15, to which are fastened, by screws 17 in the instance illustrated, the brackets 19 preferably having antirattling devices 21, 45 such as washers of elastic material, interposed between the strips or pipes 13 and brackets 19.

In accordance with another important 50 feature of our invention means are provided to facilitate the introduction of the balls from the pit (at the far end of the alley, looking toward Fig. 1) to the entrance of the overhead track, best seen at 23 in Fig. 2, and any suitable device may be adopted for 55 this purpose. One convenient form of such a device is shown as an elevator, or elevators, 25, of which there may be any suitable number, as for example one for each of the alleys, and the construction and arrangement of these elevators may be adapted to 60 the exigencies of individual installations.

By way of example we have shown up-right ways 27, with suitable braces 29, connected to a suitable support, as the ceiling 65 at 31, and to a shelf 33 at the rear of the

pit, and in these ways run carriages 35, of suitable structure, preferably cage-like in general arrangement, and having concave bottoms 37, serving, in accordance with an important object of our invention, to center the ball out of contact with the ways 27, thus to diminish the frictional losses of power. To eject the ball positively, overcoming this centering action, suitable means may be provided, such as the bell-crank 70 lever 39 pivoted at 41 upon the ways 27, in position to have its arm 43 engaged with the cage 35 upon arrival of the latter opposite the entrance 23 to the track 11, when the leg 47 of the lever will be swung forward, kicking the ball 2 into the adjacent entrance portion 23, of the overhead track 11, whence the ball may run by gravity, in well-known fashion, along the track to the approach portion 51 and supply rack 53, 80 suitable means being preferably provided to check the momentum of the balls 2 at the region of their delivery to the supply rack, 85 as will be more fully described hereinafter.

In order to permit the use of a single 90 track for the balls delivered by a plurality of elevator carriages 35, without such interference as might result in the displacement of one or more balls from the track, we prefer to provide means of any suitable character, to regulate the procession of the balls, 95 and preferably this is accomplished, in the instance illustrated, by supporting at different levels the track strips 13 and 14 of which the adjacent entrance portions are 100 respectively composed, this arrangement being clearly illustrated in Figs. 2 and 3, in which the strips 14 are shown upon a higher initial plane than the strips 13, but curved around to lead the ball 22 into the same 105 main track 11 as the ball 2, with the effect that if two balls as 2 and 22 arrive simultaneously at the junction, the ball 22 at the higher level will over-ride the lower ball 2 and precede it into the common track 11, 110 and the ball will not be jammed by the encounter.

At the approach end of the bowling alley, where the balls are delivered to the supply rack 53, as already noted, suitable means 115 are preferably provided to check the momentum of the balls, which as will readily be understood, will tend to be in proportion to the height of the overhead track, relatively to the supply rack; and accordingly 120 an important object of our invention resides in the means to control the delivery of the balls, which means may be of any suitable character. By way of example, we have shown a tortuous track portion 55, strongly 125 supported as at 57, and preferably comprising reverse curves 59, 61 so that the acceleration of the ball 2, in its descent in a relatively short lateral space, is effectively checked, and the ball arrives in spent con- 130

dition at the supply rack 53. The degree to which this tortuous portion of the track is extended may be varied in accordance with the exigencies of individual installations, and in the instance illustrated we have shown a portion 58 below the level of the supply rack 53, so that the ball must traverse an upward rise 62 before entry to the supply rack, but in many instances the reverse curve 55, 61 will serve to check the momentum and the track may lead into the supply rack at substantially the slight decline illustrated in Fig. 4, without the depression of the delivery portion below the level thereof.

The provision of means to operate the elevators constitutes an object of our invention of notable importance and to serve this purpose any suitable construction may be adopted. As one suitable form of device for this purpose we have shown means tending constantly to maintain the elevators respectively in their elevated position, as shown in the drawings, the means 63, in the instance illustrated, taking the form of counterbalances of sufficient weight to raise the carriages 35, with the ball in place, as indicated, the weights 63 being connected to the elevator carriages 35 by flexible members 65, such as chains, running over pulleys 67. When the elevators are thus provided with counterbalances, we prefer to provide the elevators with means by which the cages may be lowered as required either by hand or automatically, or in both ways, according to the exigencies of particular installations, the means for this purpose being of any suitable form. In the instance illustrated, an operating chain 71 is led from the counterbalance 63, over a pulley 73 to a sheave 75 journaled upon an arbor 77 supported by the ceiling 15, and to actuate this sheave 75 to wind up chain 71 and raise weight 63 and thus to lower elevator cage or cages 35, we have shown chains 79, 81, of which the former may be operated by a handle 80, while chain 81 is led to a suitable power device 82, taking the form, in the instance illustrated, of an electric motor, to which current may be led, as by conductors 83, from a suitable source of current 84, so that when the circuit is closed through conductors 83, the motor 82 winds on chain 81, running it off arbor sheave 76, and winding chain 71 on sheave 75 to lift counterbalance 63 and permit cage 35 to descend, of its own weight, into position, adjacent to the pit shelf 33, to receive a ball 2, which the operator may throw into trough 91, by which it will be guided into the cage 35 when the latter is in position to receive a ball. To hold the cage 35 down in this position ready for a ball, we prefer to provide suitable means such as the catch 93, pivoted at 95 at the bottom of the elevator shaft, and hav-

ing its latch 97 normally in the upright position. The arm 93 rings a gong 99 when the arm swings into the position where it is caught.

The latch 97 stands up in the path of the ball, 2, and is knocked over toward the left, as the ball runs down from trough 91 into cage 35, the latch 97 releasing the cage, so that the latter is drawn upward by the descent of weight 63.

The control of the electrical circuits to effect this cycle of operations may be effected by any suitable means, and as one convenient form of such means we have shown a contact device 103 comprising a spring arm in position for engagement with weight 63 by which the spring arm 103 is crowded over against another contact member 105, the members 103 and 105 being in the electric circuit of the motor 82, so that whenever the weight descends into the position shown in Fig. 1, contact is made between the members 103, 105, and the electric circuit established through motor 82 from battery 84, and the motor winds up the weight as already described, the contact being maintained at 103, 105 by an electromagnet 104 included in the motor circuit and acting on spring arm 103.

When the cage 35 reaches its lowermost position ready for a ball, a contact piece 106, on the bottom of the cage, bridges two contact pieces, 107, 108 included in a short circuit bridging the magnet 104, and the current failing the magnet, it releases contact 100 spring 103, and the motor circuit being thus broken the motor stops, leaving the cage 35 held down by latch 97, ready for release of the latch by a ball rolling into cage 35 from trough 91.

Then when the latch 97 is so released, the weight 63 pulls up the cage 35 and ball 2 until the cage reaches the top and ball 2 is kicked out by lever 47, at which time weight 63 presses contact arm 103 into contact with 105, where it is held by magnet 104 while motor 82 raises weight 63 and permits cage 35 to make its return trip, at the end of which the latch 97 takes hold of cage 35, the magnet is short-circuited, the motor 115 circuit broken, and the cage awaits another ball, when the cycle of operations will be repeated automatically.

At any time that the electrical circuits fail, the operator simply has to pull the handle 80, drawing up the weight 63, and the cage 35 will descend until caught by latch 97, and the latter, when released by the entrance of a ball from trough 91, permits weight 63 to raise cage 35 and ball 2, 125 the operator having released handle 80.

Having illustrated and described our invention thus fully, and suitable means by which the same may be carried into effect, it will be understood that we do not limit 130

ourselves to the specific materials and structure illustrated and described by way of example.

What we claim as new, and desire to secure by United States Letters Patent, is:—

- 5 1. The combination with a bowling-alley; of a ball-return runway above the level of the players' heads; and means to elevate said balls from the pit to said runway.
- 10 2. The combination with a bowling-alley; of a ball-return runway above the level of the players' heads; means to elevate said balls from the pit to said runway; and means to deliver said balls at the approach for playing.
- 15 3. The combination with a bowling-alley; of a ball-return runway above the level of the players' heads; means to elevate said balls from the pit to said runway; means to deliver said balls at the approach for playing; and means to regulate the momentum of said balls at the region of delivery.
- 20 4. The combination with a bowling-alley; of an elevator for the balls; means tending to draw said elevator upward with a ball in place; means to depress said elevator; and means operated automatically by said balls, to initiate the operation of said elevating means.
- 25 5. The combination with a bowling-alley; of an elevator provided with a counter-balance tending constantly to raise said elevator with a ball in place; means operable by hand to depress said elevator; an electric motor to depress said elevator; and an electric contact device, operated by the elevator to initiate operation of said motor to depress said elevator.
- 30 6. The combination with a bowling-alley; of an elevator for the balls; and means to eject said balls from said elevator.
- 35 7. The combination with a bowling-alley; of an overhead runway; an elevator for the balls; and a lever operated by a member moving with said elevator, to engage the balls and eject them respectively into said runway.
- 40 8. The combination with a bowling-alley; of means to elevate the balls, comprising ways, and an elevator having a concave receptacle to center the ball out of contact with said ways; and means to eject said ball against the centering tendency of said concavity.
- 45 9. The combination with a bowling-alley having an overhead runway to return the balls from the pit to a supply rack adjacent the level of the players' hand of an upright portion of track connecting said runway and supply rack, and curved to spend the momentum of the ball.
- 50 10. The combination with a bowling-alley having an overhead runway to return the balls from the pit to a supply-rack, of an upright portion of track connecting said runway and supply-rack, and having reverse curves to spend the momentum of said ball.
- 55 11. The combination with a bowling-alley having an overhead runway to return the balls from the pit to a supply-rack, of an upright portion of track connecting said runway and supply-rack, and having a portion extended below the level of said supply-rack and a portion rising thereto to spend the momentum of said ball.
- 60 12. The combination with a bowling-alley of a return track, and a plurality of delivery portions constructed and arranged to deliver in predetermined precedence a plurality of balls arriving simultaneously at a given point.
- 65 13. The combination with a bowling-alley having an overhead return track, of a plurality of delivery track-portions at different heights to deliver in regular precedence simultaneously arriving balls, and thus to avoid jamming.

Signed at New York, in the county of New York and State of New York, this 27th day of August, 1912.
